UNITED STATES PATENT OFFICE.

CUTHBERT S. RICHARDS, OF BROOKLINE, MASSACHUSETTS, ASSIGNOR TO HARRY W. CROOKER, OF BOSTON, MASSACHUSETTS.

BOOT OR SHOE AND PROCESS OF MAKING THE SAME.

Application filed May 16, 1924. Serial No. 713,845.

To all whom it may concern:

Be it known that I, CUTHBERT S. RICHARDS, a subject of the King of Great Britain, residing at Brookline, in the county of Norfolk and State of Massachusetts, have invented certain new and useful Improvements in Boots or Shoes and Processes of Making the Same, of which the following is a specification.

10 This invention relates to boots and shoes designed for the corrective treatment of the foot and more particularly to the manufacture of boots and shoes having an insole adapted to the relief of such infirmities as 15 require special support of the metatarsal and longitudinal arches of the foot. Accordingly the invention comprehends a novel insole, a boot or shoe having such insole as a feature, and the process of making the insole and the boot or shoe in which it is incorporated.

It is a particular object of the present invention to produce a shoe which may be worn with relief by persons having such 25 foot infirmities as Morton toe, metatarsalgia and the like, due to weakness of the transverse arch of the foot, but which is so constructed that relief may also be obtained from pes planus, due to weakness of the 30 longitudinal arch, popularly known as "flat-foot." Frequently the same patient requires correction for both infirmities and this is provided for by the present invention.

With this object in view an important 35 feature of the invention contemplates a type of shoe having provision for the relief of one or more of the infirmities referred to, as may be requisite in any particular case, without change in its design. This is accomplished by building into the shoe an 40 insole so constructed that the salesman in the shoe store may manipulate it and combine with it such corrective elements as may be necessary to suit the particular requirements of the prospective purchaser.

More particularly a pocket is provided in the insole having a mouth, readily accessible after the shoe has been built, and into which a pad, arch support or other corrective element 45 may be thrust as may be required. The size of the pocket is such that the remedial pad or other support may be correctly positioned to relieve the particular infirmity of the wearer of the shoe, and the 55 proper longitudinal location of the correct-

ive element is determined by a definite limitation of the forward end of the pocket.

To the accomplishment of the above object and such others as may hereinafter appear, as will be understood from the following description by those skilled in the art, the invention comprises the features and combinations of parts, together with the novel process of manufacture, hereinafter described and then particularly pointed out in the appended claims.

The preferred form of the invention is illustrated in the accompanying drawing in which,

Figure 1 is a view of the novel shoe, in cross section, with a remedial pad associated with the insole. This view is taken on a plane that would pass through the metatarsal pocket of a left foot.

Fig. 2 represents a cross section through the shank of the novel shoe, the mouth of the remedial pad pocket being shown opened by lifting the inner margin of the insole.

Fig. 3 is a view of the rib side of one type of insole (that for a left shoe being shown) that may be employed, the curved dotted line indicating dry-thread stitching which forms the forward limitation of a pocket for receiving the remedial pads. In this view a remedial pad and a steel shank are both shown with the pocket by a dotted line, but they may be used independently each of the other,

Fig. 4 is a view of the grain side, or sock face of the insole shown in Fig. 2. In this view another type of remedial pad is shown within the pocket bounded forwardly by the dry-thread stitching,

Fig. 5 is a view, in cross section, through the shank of the type of insole shown by Fig. 3, illustrating certain steps of its manufacture,

Fig. 6 is a view, similar to Fig. 5, illustrating a further step in manufacture of said insole, and

Fig. 7 is a perspective view of one type of remedial pad.

In the embodiment of the invention illustrated in the drawing the Goodyear welt type of shoe is shown having incorporated therein a reinforced insole of the Economy type, and this type of shoe will be utilized to explain the nature and purpose of the invention. Those skilled in the art will recognize, however, that the novel features

100

105

110

of the invention may be embodied in other types of shoes, or in Goodyear welt shoes having other types of reinforced, manufactured or other laminated insoles.

5 The novel insole will be described first, and then its manner of incorporation in the shoe will be explained, providing for its manipulation in the completed shoe to transform an ordinary shoe into a shoe for correcting such infirmities as have been referred to.

Referring first to Fig. 3 which, in certain particulars, illustrates the ribbed side of a completed Economy type insole, such as is disclosed in Letters Patent of the United States to Albert E. Johnson, No. 849,245, dated April 2, 1907, it will be observed that the body 10 of the insole is provided with a marginal rib 12 throughout the shank and

20 fore part as is requisite in the manufacture of Goodyear welt shoes. The blank is fitted by producing a marginal lip 14 and a parallel marginal channel flap 16 joined at their bases to the between-substance 15. The lip 25 and flap in the usual process of manufacture are then raised, cemented together and finally reinforced by the application of a sheet of reinforcing material 20, such as cotton duck, to the ribbed face of the insole.

30 In the present instance before the upstanding rib 12 is formed, the channel flap, preferably at the inner side of the shank, is slit twice transversely conveniently while still lying in the channel. One slit 18 35 (dotted line Fig. 3) is formed slightly to the rear of the inner end of the ball line, and the other slit 19 is formed a short distance in advance of the inner end of the breast line. When the rib forming operation occurs the portion 16^a of the channel flap, between the slits 18 and 19, is not raised. This portion of the channel flap 40 still remains lying in the channel during the operation of applying the reinforcement

45 20, the margin of which is cemented to the inner surface of the sewing-rib throughout its length and also to the unraised portion 16^a of the channel flap. The shank of the insole, at this stage of its manufacture, is

50 illustrated by Fig. 5. Thereafter the between-substance 15^a between the channel flap slits 18 and 19, is completely severed from the insole body, see Fig. 6, thus forming an opening or mouth through which access may be had to the pocket 21 between the body

55 10 and its reinforcement 20. The size and more particularly the forward boundary of this pocket is determined by a line of dry-thread stitching 22, indicated by a dotted line on Figs. 3 and 4, which extends in a curve transversely across the insole, following generally the forward ends of the bones forming the metatarsal arch of the foot. This stitching secures the body and

65 definite limit to the forward extension of the pocket 21.

In the manufacture of flexible shank shoes it is found desirable to continue this stitching rearward through the length of 70 the channel at the outer side of the insole. This continuation of the stitching is shown at 23, just inside the sewing rib 12 and is found to give enough rigidity or reinforcement to a flexible shank to balance the outward throw of the foot when right and left 75 heels are used, as is contemplated in the construction of the shoes manufactured in accordance with this invention. The transverse and longitudinal portions of the stitching 80 together form a line simulating a question mark with the tail in the outside channel (see Figs. 3 and 4).

The formation of the insole having been completed, as explained, it is incorporated 85 in the shoe in the usual manner. Upper materials 24 are lasted in over the feather, a welt 26 is inseamed to the sewing-rib 12, cork or other filling 28 is applied if necessary, and an outsole 30 is stitched to the 90 welt 26 (see Fig. 1). It will be observed, however, that the inseam, between the flap slits 18 and 19, passes through the sewing-rib above the plane of severance of the between-substance 15^a from the body 10, as indicated by the small curved line 27 on Fig. 6. This leaves the margin of the insole, along the inner shank, free to be lifted from the parts beneath it, which are firmly held to the outsole by the inseam and outseam. 100 By reaching into the completed shoe and lifting the insole, as illustrated in Fig. 2, the mouth of the pocket 21 is opened and the shoe salesman may then insert such corrective element or elements as are required 105 to relieve the foot infirmity from which his customer is suffering.

Infirmities of the foot may be placed in two general groups, those due to a weakness 110 of the metatarsal arch and those due to a weakness of the longitudinal arch. The manner in which the insole is manipulated to correct some of the foot infirmities resulting from such weak arches will now be described.

115 "Morton toe" is a condition resulting from the fourth metatarsal dropping to a lower plane than is normal for this bone, causing painful pressure on one or more of the plantar nerves. Relief from this pressure may 120 be obtained by a wedge under the extreme outer side of the metatarsal pocket supporting the fourth metatarsal at a point back of the forward ends or heads of the three central bones which form this pocket. Accordingly a pad 32 having the characteristic form shown by Fig. 7 is inserted in the pocket 21 through its opened mouth and then positioned as shown by dotted lines 125 on Fig. 4 at the outer edge of the metatarsal 130

sal pocket with a pointed end forward under the weakened bone so that this bone is raised and supported in its correct relation to the other bones of the metatarsal arch.

- 5 Metatarsalgia is the result of weakened muscles and ligaments that allow the second, third and fourth metatarsals to drop into a lower plane than the first and fifth. This also causes painful pressure on one or 10 more of the planta nerves which is relieved only by restoring the metatarsal arch to its natural formation. In correcting this infirmity a remedial pad 34, of the form shown by dotted lines in Fig. 3, is inserted in the 15 pocket 21 and placed centrally thereof, or below the central position of the metatarsal pocket, thus supporting and restoring the arch.

Pes planus is the well known "flat foot" 20 and involves a breaking down of the longitudinal arch of the foot due to weakness of the muscles and ligaments. This condition may be relieved by placing a light, steel shank 36, indicated by dotted lines in Fig. 25 3, under the central portion of this arch. Such a shank may readily be inserted in the proper location in the rear portion of the pocket 21 and then tacked in place.

The above explanation will indicate the 30 manner in which various foot infirmities are corrected or relieved by means of the present invention, it being understood that the particular infirmities described are only by way of example. Attention is called especially to the size of the pocket 21 i. e. the considerable area of the face of the insole body over which it extends. This construction provides a single insole pocket which may be utilized for the reception of the different remedial elements for the correction 40 of all known foot infirmities, with the advantage that a special insole need not be constructed for correcting each infirmity. Attention is especially called to the fact that 45 all this provision is made in a regular insole adapted to be incorporated in the shoe during its manufacture, and so constructed that it can be utilized for this purpose after it has been made a part of the shoe. Having the 50 shoe with the novel insole built into it, it only remains to select the proper corrective element and then position it correctly within the pocket. The stitching 22 effectually prevents the remedial pad from creeping forward and thus becoming misplaced, and the 55 size of the pocket permits ample adjustment to suit the form of the wearer's foot, which may have short toes and a long arch or vice versa. The nature and construction of the 60 pads may be varied as becomes desirable. In practice excellent results have been obtained with pads formed from crêpe rubber and from felt.

While access to the pocket 21 may be had 65 more conveniently through a mouth opening

at the inner side of the shank, it is within the scope of the invention to form the mouth at the outer side of the shank if desired. While the invention has been shown as applied to one well known type of insole, it 70 will be understood that it is readily applicable to other types of insoles, and is not limited to the illustrative embodiment except as specified in the appended claims.

The nature and scope of the invention 75 having been indicated and the preferred construction of the insole, the shoe, and the process of their manufacture having been specifically described, what is claimed as new, is:—

1. A boot or shoe comprising upper materials and a built-in insole provided with a marginal sewing-rib, said rib being connected to the body of the insole except along the shank at one side where it is disconnected 85 therefrom to form the mouth of a pocket beneath said body, an under layer secured to said rib between which and the insole body said pocket is formed, and means for securing said upper materials 90 to said rib and under layer.

2. A boot or shoe comprising upper materials and a built-in insole provided with a marginal sewing-rib, said rib being connected to the body of the insole except along 95 the shank at one side, an under layer secured to said rib and free from the body throughout a portion of its forepart and shank, a line of stitching across the forepart and connecting said body and under layer to 100 limit the forward extension of the pocket formed therebetween to which access is had through the mouth formed by said unconnected rib portion, and means for securing said upper materials to said rib 105 and under layer.

3. A boot or shoe comprising upper materials, an insole and an outsole, said upper materials being attached to the insole at its margin, and said insole being formed 110 of at least two layers of material the under layer adjacent the outsole being held to the upper materials by securement thereto throughout the length of its margin, and the upper layer also being marginally secured to the upper materials except for a portion of its edge between the ball and breast lines, whereby, on reaching inside the shoe said upper layer may be lifted from said under layer and thus gain access to the 120 pocket between said layers.

4. A boot or shoe comprising upper materials, an outsole and a laminated insole the layers of which are separable to form a pocket between them, and means for securing the upper materials to all the layers of the insole around the forepart and along the outer edge of the shank and only to the layer adjacent to the outsole along the inner edge of the shank, whereby, in the com- 125 130

pleted shoe, the margin of the upper layer may be lifted from the parts beneath it.

5. The method of making boots and shoes which includes the steps of assembling a ribbed insole blank and an upper on a last, said insole having a reinforcing layer which is secured by its margin to the rib but is unsecured to the shank and ball which it underlies, securing the margin of 10 the upper and a welt to both the insole blank and its reinforcement throughout the length of the rib except at the one side of the shank where the securement is to the reinforcement only, and then completing 15 the shoe by securing an outsole to said welt.

6. The method of making boots and shoes which includes the steps of preparing a laminated insole with its layers marginally secured together except at the inside shank, 20 stitching an upper to said insole by a seam through the margin of the upper and both insole layers except at said inside shank, stitching to the under layer only at said inside shank, and then completing the shoe 25 by bottoming.

7. An insole having a marginal sewing-rib throughout its shank and fore part, said rib being attached to the insole except substantially from the ball line to the breast line at the one edge of its shank, and a sheet 30 of reinforcing material within said rib and secured thereto by its margin but unsecured to the face of the insole at its shank and ball portions forming a pocket having a mouth constituted by the unattached portion of said rib.

8. A laminated insole having the layers thereof marginally connected except at one edge of its shank from a point adjacent the ball line to a point adjacent the breast line where they are unconnected, and a line of 40 fastenings across the insole forward of the ball line to determine the forward limit of the pocket formed by said layers and 45 entered through said unconnected margin.

9. A laminated insole having the layers thereof marginally connected except at the inner edge of its shank which is left unconnected to form a mouth for the pocket 50 between said layers, means to define the forward limit of said pocket, and means to reinforce the shank opposite said pocket mouth.

10. An insole of the Economy type comprising a channeled blank having its flap and lip upturned to form a sewing-rib and secured together from one end of the breast line to substantially the opposite end of the ball line, and with its lip only upturned 55 rearward from said last named point to a point near the other end of the breast line, a reinforcement on the ribbed face of the insole marginally secured to the inner face

of said rib and to the upper face of the portion of the flap which still lies in the channel, said portion of the rib opposite the unraised flap being severed from the body of the insole at its base to form a mouth for the pocket between said body and reinforcement. 65 70

11. The method of making insoles which includes the steps of forming a marginal sewing rib on an insole blank, applying a reinforcement to the ribbed face of the blank and securing said reinforcement to 75 the inner face of the rib, and severing the rib from the blank along one side of the shank thereof.

12. The method of making insoles which includes the steps of forming a marginal flap and lip on an insole blank; slitting the flap transversely a short distance forward of one end of the breast line, and substantially at the end of the ball line on the same side; raising the lip and securing the flap thereto, except that portion of the flap between said slits, to form a sewing-rib; applying a reinforcement to the ribbed face of the insole body and securing its margin to the inner face of the rib and to the unraised portion of the flap; and severing the rib from the body between said transverse flap slits. 80 85 90

13. A welt insole comprising two layers unconnected to each other at the shank and ball portion thereof, and a line of stitching through said layers extending in a curve transversely across the insole forward of the ball line following generally the forward ends of the bones of the metatarsal arch of the foot, thereby forming a pocket between said layers adapted to hold a remedial pad, access to which is obtained through the unconnected shank, and one of said layers having a marginal sewing-rib 100 105 throughout its forepart and shank.

14. A welt shoe comprising upper materials; an insole comprising upper and under layers unconnected to each other at the shank and ball portion thereof, the under layer having a marginal sewing-rib throughout its forepart and shank to which the upper materials are secured, and both layers having a connecting line of stitching extending in a curve transversely across 110 115 the insole forward of the ball line following generally the forward ends of the bones of the metatarsal arch of the foot, thereby forming a pocket between said layers adapted to hold a remedial pad, access to said pocket for inserting said pad being obtained by lifting the loose shank of the upper layer from the under layer held by the upper materials; a welt secured to said sewing-rib; and an outsole secured to said welt. 120

CUTHBERT S. RICHARDS.
